US00D659657S

(12) **United States Design Patent**
Hussell et al.

(10) **Patent No.:** **US D659,657 S**
(45) **Date of Patent:** **** May 15, 2012**

(54) **LIGHT EMITTING DIODE (LED) PACKAGE**

(75) Inventors: **Christopher P. Hussell**, Cary, NC (US);
Shuying Huang, Apex, NC (US)

(73) Assignee: **Cree, Inc.**, Durham, NC (US)

(**) Term: **14 Years**

(21) Appl. No.: **29/401,692**

(22) Filed: **Sep. 14, 2011**

Related U.S. Application Data

(62) Division of application No. 29/360,791, filed on Apr. 30, 2010, now Pat. No. Des. 648,686.

(51) **LOC (9) Cl.** **13-03**

(52) **U.S. Cl.** **D13/180**

(58) **Field of Classification Search** **D13/180;**

(57) CLAIM

The ornamental design for a light emitting diode (LED) package, as shown and described.

DESCRIPTION

FIG. 1 is a top perspective view of an LED package showing our design;

FIG. 2 is a top view thereof;

FIG. 3 is a top end view thereof;

FIG. 4 is an opposing bottom end view thereof;

FIG. 5 is a bottom view thereof opposite the view of FIG. 2;

FIG. 6 is a side view thereof;

FIG. 7 is an opposing side view thereof; and,

FIG. 8 is a back perspective view thereof.

The broken lines are for illustrative purposes only and form no part of the claimed design.

1 Claim, 2 Drawing Sheets
